The ornamental design for a debris cart, as shown and described.

DESCRIPTION

FIG. 1 is a top perspective view of a debris cart showing my new design;

FIG. 2 is a front elevational view of the debris cart of FIG. 1, the rear elevational view of the debris cart being a mirror image thereof;

FIG. 3 is a left side elevational view of the debris cart of FIG. 1;

FIG. 4 is a right side elevational view of the debris cart of FIG. 1;

FIG. 5 is a top plan view of the debris cart of FIG. 1; and,

FIG. 6 is a bottom plan view of the debris cart of FIG. 1. The dash-dash-dash broken lines shown in the figures are for purposes of illustrating environment only and form no part of the claimed design.

The debris cart is shown with a symbolic break in its length. The appearance of any portion of the article between the break lines forms no part of the claimed design.
